CARBURETOR

Otto Meissner, Berlin, Germany

Application November 13, 1930, Serial No. 495,452,
and in Germany November 14, 1929

3 Claims. (Cl. 261—51)

The invention relates to carburetors for internal combustion engines, and more particularly to a spray carburetor with a fuel check and regulating valve or a fuel check or regulating valve directly controlled by the suction stroke of the engine or other suitable means and having a by-pass channel opening at the edge of the throttle member.

One object of the invention is to provide adjustable stops or abutments for controlling the fuel check and regulating member or the fuel check or regulating member when the engine runs light as well as during the transition and during the maximum output or full load.

Another object of the invention is to design the individual stops in such a way that each of them may be adjusted during the working of the engine without the other stops and the members cooperating with them being affected thereby.

A further object of the invention is to provide a stop adapted to be controlled by hand or by the throttle member which acts upon the projecting end of the fuel check and/or regulating member and which is adjustable for the purpose of regulating the no-load run of the engine.

A further object of the invention is to provide a lever in connection with the stop for controlling the fuel check and regulating member which lever is adapted to be controlled by a stop connected with the spindle of the throttle member which is adjustable for the purpose of effecting the transition regulation without the no-load position being affected.

A further object of the invention is to make provisions for the fuel quantity regulation for the maximum output taking place by an adjustable stop or the like without the no-load and transition adjustment being affected thereby.

A still further object of the invention is to provide apart from the member controlled by the suction stroke of the engine, which in this case acts merely as check member, a second controllable and adjustable check and regulating member or regulating member only between the first member and the fuel pipe.

A further novel feature of the invention is that the fuel check and regulating member is, for instance, raised by a spring and forced down upon its seat by an adjustable stop acting upon it and adapted to be controlled by hand or by the throttle member.

Another novel feature of the invention is that the no-load regulation takes place by adjusting the needle valve in relation to its seat or vice versa, and that the lever acting upon the ad-

justable stop of the fuel check and regulating member or fuel check or regulating member is adapted to be rendered operative not only by hand or by the throttle member but also by a starting device without the individual control gears affecting one another.

A still further feature of the invention is that when the mixture is supplied by the starting mechanism alone or in conjunction with the throttle member a larger quantity of fuel-air mixture and a mixture stronger in fuel is fed to the engine and that the additional quantity of fuel is adapted to be regulated by an adjustable stop.

On the drawing affixed to my specification and forming part thereof some embodiments of the invention are illustrated by way of example.

The invention is illustrated in the accompanying drawing in which:

Fig. 1 shows the improved carburetor in sectional elevation, with the check and regulating valve and the stop controlled by the throttle member or by hand.

Fig. 1^a is a diagrammatic plan view of the carburetor shown in Fig. 1.

Fig. 2 is a further embodiment of the invention in vertical section, in which a special check and regulating valve is provided in addition to the fuel valve.

Fig. 3 is a third embodiment of the invention, in which the stop for the fuel valve is coupled with a starting device, and

Fig. 4 is a still further embodiment in which the starting device also controls the throttle member.

Referring to Fig. 1 of the drawing, 1 is the casing of the carburetor with the removable nozzle pillar or shank 2. In this pillar is accommodated the fuel check and regulating valve 3 with the disc or plate 4 and needle 5. In the inoperative state the conical end 6 of the valve 3 rests upon the conical seat 7 of the nozzle pillar or shank 2 and the needle 5 projects into the bore 8. The valve 3 passes with its upper end 9 through the check or cap nut 10. Above the end 9 of the valve there is according to the invention provided a stop or abutment 11 which is adapted to be adjusted within its guide 12, for the purpose of adjusting the running light of the engine. The stop 11 and the lever 13 connected with it are pivotally mounted at an extension of the carburetor casing and are maintained in their inoperative position by a spring or by gravity.

On the spindle of the throttle 14 there is provided a stop 15 which is likewise longitudinally

adjustable, to enable adjustment to be made between lever 13 and the throttle 14. Into the cap nut 10 there is in the case illustrated screwed a screw 16 which serves as stop or abutment for the collar 17 or the like of the valve spindle 3 so that the maximum output may be regulated by adjusting the screw 16. The maximum output could naturally also be adjusted by means of the calibrating nozzle 35.

10 In the embodiment illustrated in Fig. 2 of the drawing there is in addition to the valve 3 controlled by the suction stroke of the engine also provided between this valve and the fuel supply pipe 18 a special check and regulating valve 19 with needle point 20 which is raised, for instance, by a spring 21 when the stop 11 is moved out of the way. The collar 23 resting in the inoperative state upon the seat 22 serves at the same time as stop for the maximum output of the engine when it comes in contact with the adjustable screw 16. Between the seating 22 and the fuel pipe 24, there are provided packings 25 which preferably stand under the action of springs. The running light regulation is in this case effected by the screw 26 which adjusts the fuel channel 27 in relation to the needle 20.

15 In Fig. 3 of the drawing there is illustrated an embodiment of a combination of the fuel valve 3, not shown in this figure, with a starting device. The lever 13 contacts in this case with a pin 28 of the valve 30. When the valve 30 opens the lever 13 is carried along by it and the spacing between fuel valve 3 and stop 11 is increased so that an ample quantity of fuel 20 can pass into the mixing chamber 31. When the valve 30 is opened the passage to a channel is uncovered which opens between throttle member 14 and the cylinder of the engine so that a sufficient and adequately saturated quantity of fuel-air mixture is sucked into the engine. During the motion of the valve 30 the pin 32 comes in contact with the adjustable nut 33 whereby the stroke of the lever 13 and the valve 3 or 19 is limited. If the stop 11, 13 is operated by 25 the movement of the throttle member 14 or by

hand, the pin 28 has no effect on the starting device 30. The lever 29 for imparting motion to the throttle member 14 may, as shown in Fig. 4, likewise be moved by a pin 31 of the starting device 30, so that when the starting device is opened the throttle member is likewise opened. In this case also provisions have been made for moving the throttle mechanism independently of the starting device. In all cases the stop 11 may be positively operated by hand by means of a Bowden wire or the like so that the quantity of fuel may also be regulated by hand.

80 I claim as my invention:

1. In a spray carburetor for internal combustion engines, a fuel check and regulating valve controlled by the suction stroke of the engine acting as a check member, a second check and regulating member located between said first control member and a fuel supply pipe, a spring for raising said second member, and an adjustable stop controlled by the throttling member for pressing said second member against its seat. 85

2. In a spray carburetor for internal combustion engines, a fuel check and regulating valve controlled by the suction stroke of the engine acting as a check member, an adjustable stop for regulating the quantity of fuel for the full capacity of the engine without the running light and transition period being affected, a second check and regulating member located between the first control member and a fuel supply pipe, and means for selectively effecting the running light regulation manually. 90 100

3. In a spray carburetor for internal combustion engines, a fuel check and regulating valve directly controlled by the suction stroke of the engine, a stop for said fuel check, a lever adjustably supporting said stop, a throttling member for the engine, and a second stop adjustably connected with the throttling member to cooperate with said lever to control the fuel check without the light running position of the engine being affected. 105 110 115
